UNITED STATES PATENT OFFICE.

JAMES E. MEED, OF PALESTINE, WEST VIRGINIA.

SAW-SETTING TOOL.

Application filed March 10, 1921. Serial No. 451,255.

To all whom it may concern:

Be it known that I, JAMES E. MEED, a citizen of the United States, residing at Palestine, in the county of Wirt and State of West Virginia, have invented new and useful Improvements in Saw-Setting Tools, of which the following is a specification.

This invention relates to saw setting tools and has for its primary object to provide a hand operated tool of such construction that the operation of setting saw teeth is greatly simplified and whereby all of the teeth of the saw are set at uniform angles.

A further object of the invention is to provide a saw set of such character that it may be easily operated by anyone, and wherein the teeth will be properly set at the desired angle without the exercise of special skill or knowledge.

20 A further object is to provide a tool of the character stated wherein adjustment of the device may be quickly and easily made so as to incline the teeth at any desired angle.

A still further object of the invention is 25 to provide a saw set of that character wherein an automatically operating hammer is employed for delivering a blow to the saw teeth, and wherein means of an improved nature is utilized for varying the pressure 30 of the hammer blow, thus compensating for saws having thick or thin teeth.

A still further object is to provide a saw set of the character stated further featured by improved means for adjusting the mechanism to time the blow of the hammer.

With these and other objects in view, the invention consists of the features of construction, combination and arrangement of parts, hereinafter fully described and 40 claimed, reference being had to the accompanying drawings, in which:—

Figure 1 is a side elevation of a saw set constructed in accordance with the invention, part of the casing being removed to 45 show certain parts of the underlying structure.

Figure 2 is a front elevation of the improved saw set, a part thereof being broken away,

50 Figure 3 is a central longitudinal sectional view taken through the improved saw set,

Figure 4 is a fragmentary top plan view showing in detail the means employed for automatically adjusting the saw relative to 55 the anvil,

Figure 5 is a bottom plan view of the device shown in Figure 4, the adjusting shaft being shown in section,

Figure 6 is an enlarged transverse sectional view taken on line 6—6 of Figure 4, 60

Figure 7 is a transverse sectional view taken on line 7—7 of Figure 3, and

Figure 8 is a detail perspective view of the anvil.

Referring now more particularly to the drawings, 9 indicates the main casing for the saw setting tool. This casing may be made of suitable light metal and the main portion thereof is shaped so as to adapt itself to the hand of the tool operator, and 70 is provided at its upper end with a forwardly projecting barrel portion 10. One side of casing 9 and a part of the barrel 10 thereof is closed by a removable plate 11, the latter properly housing the mechanism 75 of the tool and by reason of the same being removable, access to such mechanism may be had should repairs or adjustment of the parts make it necessary.

The outer end of barrel 10 carries a housing or support 12 which receives anvil 13, 80 against which the saw teeth are driven in the setting operation. The side of the housing or support 12 is recessed as at 14 to permit of the cutting edge of the saw being applied 85 to the anvil.

The anvil 13 comprises a polygonal rotatable body as shown, the various sides of which are adapted to be brought into operative position with relation to the saw and the blow delivering mechanism of the tool, in order that the proper and desired angularity may be given to the teeth of the saw with which the set is used. The polygonal surfaces are indicated at 15, and are of such 90 breadth as to properly support a portion of the saw body adjacent the cutting edge thereof, and the said surfaces of the set are so cut or shaped as to enable the saw teeth to bend at the proper place, regardless of the length 95 of the said teeth. The surfaces 15 are therefore cut away or beveled inwardly near their upper edges as at 16, and it will be understood that the beveled surfaces may be varying 100 in lengths in order that the teeth of various types of saws may be accommodated and set. To facilitate adjustment of the anvil, the various faces of the anvil may be numbered or lettered as at 17.

The body 13 of the anvil is secured to the 110

longitudinally adjustable shank 18 threaded as at 19 into the casing or housing 12, the upper end of the said shank is suitably mounted in the bearing 20, and washers 21 carried by the said shaft maintain the anvil in proper position thereon. By this construction it is obvious that rotation of the shaft will enable the various surfaces of the anvil body to be brought into proper position for the accommodation of the saw blade, and the said anvil will be raised or lowered according to the direction of movement imparted to the screw shank. The lower end of this shank is equipped with a head 22 to facilitate its manipulation by the fingers.

In order that the anvil may be firmly held in its various positions of adjustments, the same is provided upon its under surface with notches or recesses 23 to receive the upper end of locking pin 24 carried by the casing. This pin is normally held seated in the recesses or notches 23 by means of the leaf spring 25.

The means for forming or shaping the teeth of the saw blade against the adjacent surface of the anvil comprises a plunger indicated at 26. This plunger is mounted for reciprocation within the hollow barrel portion 10 of the tool, and is shaped at its forward or operative end as shown so as to properly engage the teeth of the saw blade indicated at 27. The plunger is so disposed or arranged within the barrel as to deliver its pressure upon the saw tooth normally above the juncture of the beveled faces 16 with the flat faces 15 of the anvil. However, the position of contact may be accurately adjusted by manipulation of the screw shank 18 supporting the anvil.

The body or casing 9 of the tool is provided near its forward face with a lever 28, the latter being pivoted within the body as at 29. This lever conforms to the shape of the fingers as the hand clenches the tool, and is retracted or moved inwardly upon its pivot as the grip of the hand is tightened. As the grip is relaxed, however, the lever moves outwardly or forwardly under impulse of expansion spring 30 interposed between the said lever and the body or casing 9. The upper extremity of this lever is headed as at 31 and this head fits within a recess 32 at the rear end of plunger 26. It is obvious, therefore, that as the lever 28 moves inwardly or rearwardly, the plunger 26 will be advanced or moved toward the anvil, and as the lever 28 moves outwardly, the said plunger will be retracted.

The tool is provided with an auxiliary plunger 33, the same underlying plunger 26 and movable with the latter, the function of plunger 33 being to engage the saw blade below the juncture of the teeth therewith simultaneously with or just prior to engagement of the plunger 26 with the said teeth.

This auxiliary plunger 33, therefore, acts as a holding member for the saw during the setting stroke of the tool. The rear end of plunger 33 is provided with a recess 34 to receive head 35 carried by an upwardly extending resilient arm 36 carried by lever 28. The particular construction of the plungers and the manner in which they are connected with the operating lever 28 causes both plungers to be advanced or moved forwardly simultaneously with the retraction of lever 28, yet plunger 26 will be permitted to have slight longitudinal movement relative to plunger 33.

The means for delivering the setting blow to the plunger 26 comprises a hammer indicated at 37. This hammer is pivoted at its lower end as at 38 within the casing 9 and in such position that the hammer face 39 thereof contacts the rear end of plunger 26. The hammer 37 is driven forward by leaf spring 40, the latter engaging at its upper end with notch 41 in the rear edge of the hammer body above the pivot 38 thereof. The lower end of this leaf spring extends downwardly through the body or casing 9 and is seated in an adjustable block 42 near the lower end of said casing. This block travels in guides 43 disposed longitudinally of the body 9, and the lower end of the said block is engaged by lever 44 pivoted at one end as at 45 within the said casing. The outer end of the lever is rounded and internally threaded to receive the threaded shank 46 rotatably mounted within the said casing and provided at its lower end with a milled wheel 47, to facilitate manipulation of the threaded member with the fingers. It will be observed that this wheel 47 is disposed upon the exterior of the casing, and it is obvious that the tension of spring 40 may be increased or diminished accordingly as the threaded shank 46 is rotated. This particular mechanism enables the degree of spring pressure applied to the hammer to be accurately controlled.

The means for causing the hammer head to be cocked or retracted against the pressure of spring 40, so as to tension the latter, includes a link 48 pivoted as at 49 intermediate its ends to a lever 50 pivoted at one end as at 51 within the casing 9. The upper end of link 48 has pivotally secured thereto a pawl 52 adapted to engage at its outer end behind a shoulder or notch 53 in the lower edge of hammer 37, and this pawl is held yieldably engaged with the adjacent edge of the hammer by a leaf spring 54. The lower end of link 48 is pivotally connected at its lower end as at 55 to the rear end of a bar or connecting member 56; the latter extending through an aperture in the forward face of casing 9 and being connected as at 57 to lever 28.

The rear end of lever 50 is rounded and

internally threaded so as to receive the upper end of screw shank 58. This screw shank has its lower end projecting through casing 9 and provided with a finger grip 59, and 5 while being capable of rotating freely, is held by washer 60 against longitudinal movement. By this construction it is obvious that adjustment of link 48 toward or away from hammer head 37 may be easily 10 and quickly made, and this adjustment determines the timing of the hammer operations.

The saw setting tool is equipped with mechanism of an improved nature for automatically adjusting the saw relative to the tool as the latter is manipulated. This mechanism is actuated by the plunger 33 and is arranged upon the barrel of the tool adjacent to the toothed edge of the saw. 15 More particularly, this mechanism includes a shaft 61 mounted at its ends in suitable bearings 62 in a casing 63 mounted upon the outer end of the barrel and overlying the plunger and anvil mechanisms. This 20 shaft or rod 61 is disposed transversely of the barrel and is disposed adjacent to the cutting edge of the saw within slot or recess 14. The shaft has adjustably secured thereon a bracket 64 carrying a pair of 25 pawls 65 adapted to engage with the upwardly extending teeth of the saw 27. The shaft is also equipped with spring clips 66, one arranged upon each side of bracket 64, to receive and maintain either or both of 30 pawls 65 when the latter are raised. In practice, one of the pawls 65 only will be engaged with the saw teeth, depending upon the direction it is desired to have the saw 35 travel during operation of the tool, and at 40 such time the other pawl 65 will be raised and held by clamp 66. The bracket 64 is maintained in adjusted positions upon shaft 61 by set screws 67, the latter extending through a slot 68 in casing 63 so that the 45 same may be manipulated without gaining access to the interior of said casing.

The casing or housing 63 confines a pair of bell-crank levers 69—70, the forward ends of which project through suitable openings or slots in shaft 61, said slots being disposed equidistant from the center of the shaft. It will be observed, particularly with reference to Figure 4 of the drawings, that the bell-cranks 69—70 are disposed opposite to each other, the lower arms 71 of said levers projecting toward each other near the longitudinal axis of the barrel of the tool. These short arms 71 of the bell-crank levers are to be engaged one at a time 55 with the forward end of a link 72 connected at its rear end to a pin 73 extending upwardly from and movable with plunger 33. Pin 73 extends through an elongated opening 74 in the plunger 26 which overlies plunger 33. Link 72 is engaged with the

short arms 71 of bell-cranks 69—70 by means of a pin 75 having a finger grip 76 at the upper end thereof, the said pin extending through a slot 77 in casing 63. By so constructing the device, the pin 75 may be moved upwardly to disengage itself with one of the short arms 71 of the bell-cranks and the link may be readily moved laterally so that the pin 75 thereof may be aligned with the opening at the inner end of the next adjacent bell-crank lever arm 71, whereupon said pin may be engaged within said opening to establish connection between the said bell-crank lever and the said link. This construction enables the direction of operative movement of shaft 61 to be reversed when desired or required.

In operation, the anvil is adjusted so that the proper face 15 thereof at the desired elevation will be presented to the saw edge, and the feed mechanism is adjusted so as to cause the saw to be fed in the proper direction through the slot or channel 14 at the outer end of the barrel. It will be understood that after the anvil is adjusted it will be held rigidly in position by means of the locking pin 24. When the tool has been applied to the saw by causing the latter to enter channel or slot 14 with the saw tooth thereof resting against the anvil, the lever 28 is retracted by contracting the hand. This movement of the lever at once starts plungers 26 and 33 moving forwardly. The plunger 33 engages the saw below the base of the tooth thereof and presses it firmly against the adjacent face 15 of the anvil. During this movement, pin 73 moving forwardly causes link 72 to similarly travel whereby the bell-crank lever with which it is attached will be caused to move shaft 61 in one direction. This movement of the shaft, causes its operative pawl to play or idle over saw tooth, and it will be understood that after plunger 26 has operated to engage a saw tooth, and both plungers 26 and 33 are being retracted by expansion of spring 30, the operative pawl 65 of the lifter mechanism will engage with a tooth of the saw and cause the saw and saw set to move relatively to each other a distance equal to one saw tooth. It will be observed, particularly with reference to Figure 3 of the drawings, that the opening 32 in plunger 26 is slightly larger than head 31, whereby slight play between the head and plunger is permitted. When initial movement is given to lever 28, head 31 will move to the forward edge of recess 32, thus permitting the said plunger to move a slight distance still further forwardly after advancing movement of head 31 has ceased. As lever 28 moves rearwardly, arm 56 causes link 48 to rock upon its pivot 49, giving forward movement to the upper end of said link. The forward movement of said end of the link

develops rearward rotary movement in hammer 37 by means of pawl 52. This rearward movement of the head continues until just prior to the time lever 28 reaches its 5 rearmost movement, whereupon the riding of pawl 52 upon the eccentric projection 78 at the lower end of hammer head 37 causes the said pawl to be disengaged at its forward end from shoulder 53 of the hammer, where- 10 upon the latter is released to the action of spring 40. The hammer at once moves forwardly under impulse of the said spring which has been tensioned by cocking of the hammer head, and the blow delivered by 15 hammer face 39 against the rear end of plunger 26 causes the latter to move forward sharply, engaging the tooth of saw 27 and forcing the same against the inclined face 16 adjacent thereto. Should it happen 20 that the blow delivered lacks force sufficient to flatten the tooth against the said inclined face, the power or tension of spring 40 may be increased by moving block 42 upwardly. This movement or adjustment is accom- 25 plished by manipulation of finger grip 47 of threaded shank 46, as has been above de- tailed. Relaxation of the grip upon the lever 28 enables the latter, by impulse of spring 30, to assume normal or extended po- 30 sition, and heads 35 and 32 will cause plungers 33 and 26 to be retracted. Simulta- neously with said retraction, the saw feeding mechanism will be caused to operate in the manner above described. As plunger 26 35 moves rearwardly so does the hammer 37 until the shoulder 53 thereof assumes normal position. As lever 28 moves forwardly the upper end of link 48 is retracted, caus- ing pawl 52 to slide rearwardly and to drop 40 in behind shoulder 53. The mechanism is thus reset for the next operation. Adjust- ment of the link 48 within the casing 9 by manipulation of hand wheel 59 will govern the time of dropping of trigger or pawl 52, 45 as will be obvious.

From the foregoing it is obvious that I have provided a saw setting tool of com- paratively simple construction and thor- 50oughly capable of performing the functions for which it is designed. The various parts of the mechanism are of such construction and assemblage as to minimize friction and to overcome as far as possible wear, break- age or derangement. As the various mov- 55 able parts of the mechanism are securely housed within the tool there is little or no danger of the same becoming disordered by being tampered with, and there should be little or no necessity for removing the cover 60 of the casing, except occasionally for oiling or cleaning purposes.

While the foregoing is a description of the invention in its preferred embodiment, it is obvious that the invention is not necessarily 65 restricted thereto, as changes in the make-

up, proportion and assemblage of parts may be resorted to without departing from the invention as defined by the claims.

Having thus fully described my invention, I claim:

1. In a saw setting tool, a plunger for operating upon the teeth of the saw, a rotatable anvil disposed in the path of said plunger, said anvil having a plurality of surfaces adapted one at a time to be presented to said plunger, said surfaces being graduated so as to vary the angle of the saw tooth pressed against said surface by said plunger, means for rotating and simultaneously vertically adjusting said anvil, and means for holding said anvil fixed against rotation and vertical movement in its various positions of adjustment. 70 75 80

2. In a saw setting tool, an anvil, said anvil being of polygonal shape and adapted to have its various surfaces presented one at a time to the saw tooth to be operated upon, a rotatable shaft supporting said anvil, said shaft being mounted in a threaded bearing so that exact adjustment of said anvil may be made, a locking pin to engage with said anvil to hold the latter in adjusted positions, and a spring engaging said pin and normally holding the latter in engagement with said anvil. 90 95

3. In a saw setting tool, a casing, a barrel communicating with said casing, a plunger moving longitudinally in said barrel, means for reciprocating said plunger, an anvil arranged in the path of said plunger, and a support for the anvil mounted on said barrel, said support being operative for rotating said anvil and also adjusting the same transversely to the axis of said barrel. 100

4. In a saw setting tool, a casing, an anvil, a plunger mounted for reciprocation in said casing and toward and away from said anvil, an auxiliary plunger movable simultaneously with the said first-named plunger, and means whereby the first-named plunger may have greater longitudinal movement in one direction than said auxiliary plunger. 105

5. In a saw setting tool, a casing, a barrel communicating with said casing, an anvil arranged at the mouth of said casing and adapted to have the toothed edge of a saw disposed against the same, a plunger movable toward and away from said anvil, an auxiliary plunger movable toward and away from said anvil, said auxiliary plunger adapted to engage said saw beyond the cutting teeth thereof and to press said saw against said anvil, means for moving said plungers, and hammer mechanism in said casing adapted to deliver a blow to said first-named plunger after the auxiliary plunger has been brought into contact with the saw. 115 120 125

6. In a saw setting tool, an anvil, a plun- 130

- ger movable toward or away from said anvil, a lever for moving said plunger a predetermined distance on its working stroke, a hammer for delivering a blow to 5 said plunger, spring means for moving said hammer in one direction, means governed by the movement of said lever in one direction for retracting said hammer against said spring means, and trigger mechanism 10 operable when the plunger has moved such predetermined distance on its working stroke for releasing said hammer to the action of said spring means.
7. In a saw setting tool, a casing, a barrel 15 communicating with said casing, an anvil disposed at the mouth of said barrel, a plunger in said barrel movable toward and away from said anvil, a lever carried by said casing and connected to said plunger 20 for moving the latter in both directions, a hammer in said casing to deliver a blow to the rear end of said plunger, a spring for forcing said hammer in one direction, trigger mechanism in said casing for cocking 25 said hammer when the plunger is advanced, and means operable when the plunger is moved a predetermined distance for releasing said hammer to the action of said spring.
- 30 8. In a saw setting tool, a casing, a plunger movable within said casing, a lever pivoted to said casing and connected with said plunger to move the latter, a hammer in said casing adapted to deliver a blow 35 to the rear end of said plunger, a spring to force said hammer in one direction, a link in said casing, a pawl carried by said link and engaged with said hammer, a connection between said link and said lever 40 whereby retraction of the latter will cause said pawl to retract said hammer, and a cam face on said hammer to engage said pawl and move the same out of contact with the hammer when the latter has been retracted a predetermined distance.
- 45 9. In a saw setting tool, a casing, a plunger carried by the casing, a lever pivoted to the casing and connected to said plunger for moving the latter, a hammer pivoted in said 50 casing adjacent the rear end of said plunger, a spring normally forcing said hammer into engagement with said plunger, a shoulder on said hammer, a link pivoted intermediate its ends within said casing, a pawl carried by one end of said link and normally 55 engaged with said shoulder, an arm connecting said lever with the opposite end of said link whereby retraction of the lever will force said pawl against the shoulder of said hammer, and a cam on said hammer adapted when the lever has reached a predetermined degree of rotation to force said pawl from engagement with said shoulder, whereby said hammer will be released to the 60 action of said spring.
10. In a saw setting tool, a casing, a plunger movable within said casing, the said plunger having a notch therein, a lever pivoted to said casing, a head carried by said lever and engaged in said notch, said head 70 being of smaller size than said notch, a hammer in said casing adapted to deliver a blow to said plunger, means for forcing said hammer in the direction of said plunger, and means governed by the movement of said 75 lever a predetermined distance in one direction to release said hammer to the action of said forcing means.
11. In a saw setting tool, an anvil, a setting plunger movable toward and away 80 from said anvil, an auxiliary plunger movable toward and away from said anvil, a lever, a resilient member connecting said auxiliary plunger with said lever, a rigid member connecting said lever with said setting plunger, and means governed by the movement of said setting plunger a predetermined distance for delivering a blow to the said setting plunger.
12. In a saw setting tool, a casing, a plunger mounted for reciprocation within 85 said casing, a hammer to deliver a blow to said plunger, a shoulder on said hammer, an arm pivoted within said casing, a link pivoted intermediate its ends to said arm, 90 a pawl carried by one end of said link and engaged with said shoulder, a cam on said hammer to disengage said pawl from said shoulder when said hammer has been retracted a predetermined distance, means for 95 rocking said link, and means for adjusting said arm toward or away from said hammer.
13. In a saw setting tool, a plunger, a pivoted hammer, said hammer adapted to 100 deliver a blow to said plunger, a spring engaged at one end with the rear of said hammer, a movable block, the opposite end of said spring being seated in said block, a pivoted arm, the said pivoted arm supporting said block, and means for swinging said arm upon its pivotal support whereby said block may be moved toward or away from 105 said hammer.
14. In a saw setting tool, a reciprocating 110 plunger adapted to operate upon the teeth of a saw, a shaft slidable transverse to the direction of movement of said plunger, a bracket secured to said shaft, pawls pivoted to said bracket and adapted one at a time 115 to be moved into engagement with the teeth of the saw, a pair of oppositely disposed bell-crank levers having their forwardly projecting arms engaged with said shaft, a link connected with the plunger at one end, 120 and means whereby the opposite end of said link may be connected with either of the rear arms of said bell-crank levers.
- 125 In testimony whereof I affix my signature.

JAMES E. MEED.
